MICHAEL LIPTAK, OF ST. PAUL, MINNESOTA

DRUM MOUNTING FOR BOILERS

Application filed August 25, 1930. Serial No. 477,785.

My invention relates to boilers of the bent tube type and is directed to an improved drum mounting especially adapted for the mounting of mud drums of such boilers. Generally stated, the invention consists of the novel devices, combinations of devices and arrangement of parts hereinafter described and defined in the claims. In boilers of the above indicated type, the mud drums are hung below the upper drums and are connected thereto by a very large number of water tubes. These numerous water tubes because of their varying lines and extent of expansion and contraction, tend to shift the mud drum transversely of its axis, laterally upwardly and downwardly. When the ends of the mud drum are set into the furnace walls against unyielding refractory blocks or material, the strains put upon the mud drum will frequently crack the unyielding refractories and cause leaky joints between the water tubes and mud drum. To avoid this, a yielding pack such as asbestos rope has been placed in the joint between the mud drum and the surrounding unyielding refractories, but this has not been found very satisfactory for the reason that such packing being very easily compressed, will allow the metallic parts of the drum to settle onto or against the unyielding refractories and at the same time will open up joints between the drum and the refractories.

My invention provides a greatly improved structure which is capable of being manufactured at comparatively low cost and rapidly and accurately erected and which, when installed, will be durable and highly efficient under all conditions.

Several commercial embodiments of the invention are illustrated in the accompanying drawing, wherein like characters indicate like parts throughout the several views.

Referring to the drawing:

Fig. 1 is a view chiefly in elevation but with some parts sectioned on the line 1—1 of Fig. 2 and with some parts broken away showing the mud drum, the furnace wall and the improved mounting;

Fig. 2 is a section taken on the line 2—2 of Fig. 1;

Fig. 3 is a fragmentary section taken on the same line as Fig. 2, but with parts broken away and with the lower portion of the drum and wall on a larger scale than in Fig. 2;

Fig. 4 is a perspective view showing one of the pliable refractories that form a ring contacting with the drum;

Fig. 5 is a perspective showing one of the refractory tiles that form a ring surrounding the ring of pliable refractories;

Fig. 6 is a view corresponding to Fig. 3 but illustrating a slightly modified structure; and

Fig. 7 is a view corresponding to Fig. 6 illustrating a still further slightly modified structure.

The mud drum illustrated in Figs. 1, 2 and 3 is of a type wherein the cylindrical drum shell 8 is provided with heads 9 lapped therewith and secured thereto with airtight joints by rivets 10. The outer drum head 9 is provided with a customary manhole 11 adapted to be normally closed by a suitable manhole cover not shown. The water tubes that connect the mud drum to the upper drums, not shown, are indicated by the numeral 12 and these, as is customary, are closely spaced both circumferentially of the drum and axially of the drum. The wall in which the outer end of the mud drum is mounted is shown as made up chiefly of outer common brick 13 and inner fire brick 14, but the outer wall portion 13 includes common brick or tile 15 arranged to form an annular ring or layer, the interior of which as shown is concentric with and approximately the same diameter as the exterior of the drum 8.

The drum mounting is made up of an inner layer of blocks 16 of an outer layer of blocks 17. The blocks 16 are circumferentially disposed in the form of a ring around and in contact with the exterior of the end of the drum 8 and the outer block 17 are circumferentially disposed in the form of a ring around and in contact with the inner blocks 16. The inner blocks 16

are of a highly refractory pliable material such as asbestos, magnesia or combinations of these or similar highly refractory pliable materials. In building the mounting into the wall structure I have found it advantageous before the wall is built close to the drum to adhesively secure the blocks 16 to the exterior surface of the drum by the use of silicate of soda ("liquid glass") or other suitable adhesive material, the function of which is only to hold the blocks in position temporarily and while the wall and mounting are being completed. As the wall is built up close to the mounting the lower blocks 17 of the outer mounting ring are placed in position and "settle" tile 19 are set in place under these lower and first set blocks 17. These "settle" blocks 19 are triangular in form and are formed with upper concave surfaces that correspond in their curve to the exterior surface of the outer ring. The other blocks 17 of the outer ring are laid in position only slightly in advance of the building of the wall structure. A filling material 20 of dry mineral wool, cement or the like is placed in the annular joint space formed around the head of the drum just outward of the inner blocks 16 and inward of the blocks 15. The inner blocks 16 on their inner faces are formed with anchoring grooves 21 that extend circumferentially of the drum and receive the outer heads of the rivets 10, thereby locking the blocks 16 to the drum, against movements longitudinally of the drum but with freedom for adjustments around the drum so that said blocks can assume the proper positions in the inner ring formation. This groove structure is shown in Figs. 1, 2, 3, 4 and 6. To interlock the inner blocks 16 to the outer blocks 17, the former are shown as provided with outwardly bulged surfaces 22 that engage correspondingly concaved surfaces 23 formed in the inner edges of the outer blocks 17. These engaging surfaces 22 and 23 lock the blocks 17 to the blocks 16 against movements longitudinally of the drum, but permit said blocks 17 to be adjusted circumferentially so that they assume their proper positions in the outer ring formation. Preferably, the blocks 16 and 17 are slightly wedge-shaped or tapered inward toward the axis of the drum. The contacting or facing surfaces of the blocks 17 are formed with grooves 24 and ribs 25 that engage the reverse formations of adjacent blocks and interlock said blocks against independent radial movements and also form lap joints. The interlocking structure is found in the structure illustrated in Figs. 1, 2, 3, 4 and 5. The structure illustrated in Fig. 6 differs from that illustrated in Figs. 1 to 5, inclusive, only in that the interlocking engagement 22-23 between the inner blocks 16

and the outer blocks 17^a is omitted. The structure illustrated in Fig. 7 differs from the structure illustrated in Figs. 1 to 5, inclusive, in that the drum 8^a there illustrated has an integral head 9^a and the rivets being omitted interlocking engagement between the drum and the blocks 17^b is omitted.

The blocks 16 and 17 may be laid either with or without cement between their joints but preferably high temperature cemented joints will be used. The blocks 16 and 17 have such relatively short circumferential length or width that by varying the cement between the joints or the angle between joints where cement is not used, they may be laid in substantially true circles of varying diameter so that the same blocks can be used as a mounting for drums that vary considerably in diameter. When the blocks are laid as described, it is evident that they will be securely held in proper drum-supporting formation regardless of various lateral, vertical, upward, downward and angular movements of the drum in its mounting. Of course, the movement of the drum in its mounting will not be great but sufficient, as already noted, to cause great damage to the parts where there is no yielding action. The pliability or resiliency in the inner blocks 16 will permit the above noted and required movements of the drum and at the same time will maintain good contact with the drum and will maintain tight joints regardless of the drum movements. Also, the drum mounting will resist high temperatures and will be found strong and durable. It is of such character that it may be laid up or installed rapidly and it is practically fool-proof in that it cannot be laid up improperly.

Obviously, various alterations or changes in the details of construction and arrangement above described may be made without departing from the spirit of the invention as herein disclosed and broadly claimed.

What I claim is:

1. A drum mounting adapted for application around the end of a drum and for application within a furnace wall, comprising a layer of highly refractory pliable inner blocks for application in ring formation around the drum, and an outer layer of rigid refractory blocks arranged for application in ring formation concentrically around said inner blocks, said inner and outer blocks having interlocking surfaces extended circumferentially of the rings and permitting said blocks to be laid with lapped joints.

2. The combination with a furnace wall and a drum extended into said wall, of a drum mounting comprising concentric layers of blocks forming concentric rings applied in said wall around said drum, certain of said blocks being of highly refractory pliable material permitting the drum to

shift in the directions radiating from the axis thereof, and settle blocks having concave surfaces seated under and against outer surfaces of the outer layer of said blocks.

5 3. A drum mounting adapted for application around the end of a drum and for application within a furnace wall, comprising a layer of highly refractory pliable inner blocks for application in ring formation around the drum, an outer layer of rigid refractory blocks arranged for application in ring formation around said inner blocks, and settle blocks having concave surfaces seated under and against outer surfaces of the outer layer of said blocks.

10 4. The combination with a furnace wall and a drum extended into said wall, of a drum mounting comprising a layer of highly refractory pliable inner blocks applied in said wall directly around an end of said drum, and an outer layer of rigid refractory blocks applied in said wall and arranged in ring formation directly and concentrically around said inner blocks, and in which said 15 inner and outer blocks have interlocking surfaces extended circumferentially of the ring formation.

15 5. The combination with a furnace wall and a drum extended into said wall, of a drum mounting comprising a layer of highly refractory pliable inner blocks applied in said wall directly around an end of said drum, and an outer layer of rigid refractory blocks applied in said wall and arranged in 20 ring formation directly and concentrically around said inner blocks, said drum at its end portion having projecting rivet heads and said inner blocks on their inner surfaces having grooves that receive and interlock with the projecting rivet heads, said inner and outer blocks having interlocking surfaces extended circumferentially of the 25 ring formation.

6. The combination with a furnace wall and a drum extended into said wall, of a drum mounting comprising a layer of highly refractory pliable inner blocks applied in

said wall directly around an end of said drum, and an outer layer of rigid refractory blocks applied in said wall and arranged in ring formation directly and concentrically around said inner blocks, said inner and outer blocks being interlocked against movements longitudinally of the drum.

7. The combination with a furnace wall and a drum extended into said wall, of a drum mounting comprising a layer of highly refractory pliable inner blocks applied in said wall directly around an end of said drum, and an outer layer of rigid refractory blocks applied in said wall and arranged in ring formation directly and concentrically around said inner blocks, said inner blocks being interlocked to the drum against movements longitudinally thereof.

8. The combination with a furnace wall and a drum extended into said wall, of a drum mounting comprising a layer of highly refractory pliable inner blocks applied in said wall directly around an end of said drum, and an outer layer of rigid refractory blocks applied in said wall and arranged in ring formation directly and concentrically around said inner blocks, said inner blocks being interlocked to said drum against movements longitudinally thereof but with freedom for adjustment circumferentially thereof, and said outer blocks being interlocked to said inner blocks against movements longitudinally of the drum but with freedom for relative circumferential adjustments.

9. The combination with a furnace wall and a cylindrical drum extended into said wall, of a drum mounting comprising concentric layers of blocks forming concentric rings applied in said wall around the cylindrical portion of said drum, certain of said blocks being of highly refractory pliable material, permitting the drum to shift in directions radiating from the axis thereof, said ring-forming blocks being interlocked to each other and to the drum against movements longitudinally of the drum.

MICHAEL LIPTAK.
